UNITED STATES PATENT OFFICE

92,650

DESIGN FOR A CAMERA CASING

Eugene Farkas, Brooklyn, N. Y.

Application August 18, 1933, Serial No. 49,055

Term of patent 7 years

To all whom it may concern:

Be it known that I, EUGENE FARKAS, a subject of the Kingdom of Hungary, residing at Brooklyn, in the county of Kings and State of New York, have invented a new, original, and ornamental Design for a Camera Casing, of which the following is a specification, reference being had to the accompanying drawing, forming part hereof.

In the drawing, Figure 1 is a front elevation of a camera casing showing my new design and shows a rectangular frame superposed upon an

octagonal frame, the four-corner sides of which are much shorter than the intermediate sides.

Figure 2 is a side elevation of the camera shown in Figure 1, and shows a centrally divided octagonal figure and a film winding key at one end.

I claim:

The ornamental design for a camera casing, as shown and described.

Signed at New York, N. Y., this 9th day of August, 1933.

EUGENE FARKAS.
